CLAIM

The ornamental design for popsicle holder, as shown and described.

DESCRIPTION

FIG. 1 is a front view of a popsicle holder in accordance with the new design;

FIG. 2 is a side view thereof;

FIG. 3 is a top view thereof;

FIG. 4 is a front perspective view thereof; and,

FIG. 5 is a bottom perspective view thereof.

The body portion of the popsicle holder is semi-transparent. The handle of the popsicle holder is opaque. Transparency is omitted in FIGS. 5 and 6 for clarity.

1 Claim, 2 Drawing Sheets

FIG. 1

FIG. 2

FIG. 3

FIG. 4

FIG. 5
